CLAIM

The ornamental design for a construction anchor for connecting horizontal and vertical support members to a base, as shown and described.

DESCRIPTION

FIG. 1 is a front perspective view showing our new design of a construction anchor for connecting horizontal vertical support members to a base, the sides not shown each being a mirror image thereof;

FIG. 2 is a bottom perspective view thereof;

FIG. 3 is a bottom perspective view of a second embodiment thereof, having the same design otherwise as shown in FIG. 1;

FIG. 4 is a bottom perspective view of a third embodiment thereof, having the same design otherwise as shown in FIG. 1;

FIG. 5 is a top perspective view of a fourth embodiment thereof, the sides not shown being the mirror image of the side shown; and

FIG. 6 is a bottom perspective view thereof, the quadrants as viewed from the bottom being symmetrical and identical design.

FIG. 1

FIG. 2

FIG. 3

FIG. 4

FIG. 5

FIG. 6
